UNITED STATES PATENT OFFICE.

JULIUS DUSEVOIR, OF OAKLAND, AND ARCHIBALD W. SLOAN, OF CONCORD, CALIFORNIA, ASSIGNORS, BY MESNE AND DIRECT ASSIGNMENTS, OF ONE-HALF TO CHARLES W. MEYRICK, OF MEQUON, WISCONSIN, AND ONE-HALF TO FRANCES E. SLOAN, OF CONCORD, CALIFORNIA.

MOP.

Application filed April 17, 1922. Serial No. 554,305.

To all whom it may concern:

Be it known that we, JULIUS DUSEVOIR and ARCHIBALD W. SLOAN, citizens of the United States, and residents, respectively, 5 of the city of Oakland, in the county of Alameda, and of the city of Concord, in the county of Contra Costa, and State of California, have made a new and useful invention, to wit, Improvements in Mops; and 10 we do hereby declare the following to be a full, clear, concise, and exact description of the same.

This invention relates particularly to an improved cleaning appliance more particularly known as a mop.

An object of the invention is to provide a handle for holding a mop in an operative position and with means combined therewith for squeezing or removing dirt, water, 20 detritus and the like from said mop.

A further object of the invention is to provide a mop handle having pressure means thereon and adapted to automatically compensate for any irregularities of thickness in the said mop.

A further object of the invention is to provide an apparatus that will be superior in point of simplicity, inexpensiveness of construction, positiveness of operation and 30 facility and convenience in use and general efficiency. Other objects and advantages will appear as this description progresses.

In this specification and the annexed drawings, the invention is illustrated in the form considered to be the best, but it is to be understood that the invention is not limited to such form, because it may be embodied in other forms; and it is also to be understood that in and by the claims 40 following the description, it is desired to cover the invention in whatsoever form it may be embodied.

In the accompanying one sheet of drawings,

Fig. 1 is a front elevation of a mop constructed in accordance with our invention.

Fig. 2 is a side elevation of Fig. 1.

Fig. 3 is an enlarged section taken through Fig. 1 on the line 3—3.

Fig. 4 is a plan section taken through Fig. 5 on the line 4—4.

Fig. 5 is a vertical section taken through Fig. 4 on the line 5—5.

Fig. 6 is a view of the mop rack.

Fig. 7 is an enlarged view of the operating handle mechanism.

In detail, the construction illustrated in the drawings, comprises a handle member 1, preferably shaped as a smooth shaft and having an enlarged head or base portion 2 on one end thereof and formed of wood or any other material. The said base 2 projects laterally on both sides of the handle to any width which may be desired. A pair of bracket members 3 and 4 are formed 60 on opposite sides of the head 2 and are adapted to have a roller 5 rotatably mounted therein.

A shaft 7 is arranged laterally within said head 2, so that the ends 8 and 9 thereof, 70 project beyond the sides of the said head. A pair of arms 10 and 11 are secured to the projecting ends of said shaft, the opposite ends of said arms having a roller 12 rotatably mounted therein and arranged so 75 as to parallel the axis of the roller provided in the head member. The roller 12 is supported so that it may be moved into and from co-operative relation with the head roller 5, whereby said rollers may be maintained in adjustable relationship. A lug 13 is secured to the shaft 7 intermediate its ends and which projects through the under side of the head 2. A lever 14 is secured to the projecting end of the said lug 13 and which 80 extends to and connects with an arm 15 pivoted to a collar 16 on said handle 1. The collar 16 is slidably or adjustably mounted on the handle 1, a compression spring 17 being adapted to bear against said collar so as 85 to force it outwardly on the said handle, thereby creating an active tension through the arm 15 on the lever 14 and roller 12. The form of pivotal connection between the end of the lever 14 and the arm 15 is in the 90 nature of an eccentric connection, so that through the pressure of the spring 17 on the pivoted end of the arm 15, it is thus possible to regulate the tensional contact or 95 adjustable relationship between the respective rollers 5 and 12. The arm 15 is so arranged that when positioned as shown in Fig. 2, the respective rollers will bear one against the other. When the arm 15 is moved to the unlocked or reversed position, the roller 12 is thrown out of contact with

the roller 5, as is shown by dotted lines in Fig. 3.

A mop 18, consisting of a flexible cloth or other suitable element and having a channel shaped member 19 removably binding the head portion thereof, is adapted to be retained between the rollers 5 and 12. The spring 17 in co-operative combination with the arm 15, lever 14 and roller 12 permits an object of any thickness to be retained between the respective rollers 5 and 12, so that the said rollers may be locked as if no object were retained between the said rollers. Furthermore, any irregularities or undulations in the mop element 18, when being drawn or passed through the rollers 5 and 12, will be compensated for or taken up by the spring 17 without danger of the arm 15 being thrown out of locked position.

The head 19 of the mop is provided with a toothed rack or extension 20 thereon which lies within a groove 21 provided on the handle 1. The groove 21 is of such depth that the rack 20 will be concealed below the surface of the handle 1. A guide clip 22 is provided around the handle for holding the rack 20 in the groove. A shaft 23 is rotatably mounted in the said clip 22 and has a handle 24 thereon. A sprocket 25 is secured to the shaft 23 within a slot provided therefor in the handle 1, the teeth on said sprocket intermeshing with the teeth provided on the rack 20 of the mop. It will be obvious that by turning the handle 24, the sprocket 25 will be rotated and through its meshing engagement with the rack 20, it will move said rack in the groove to draw said mop between the pressure rollers 5 and 12. The length of the rack 20 is such that all water or moisture may be squeezed entirely out of each portion of the mop 18. Upon the completion of the mop-squeezing operation, the arm 15 would be unlocked, thereby releasing the tension on the roller 12 and permitting the mop 18 to be lowered relative to the head 2 of said handle into operative position. After the mop has been placed in the desired position adjacent the head 2, the pressure roller 12 would be again placed in contact with the outer face of the mop so as to tightly clamp it against the head roller 5, through the action of the lever 14 and spring-tensioned handle 16. The apparatus thus described comprises an ordinary mop with mechanism which will thoroughly squeeze from said mop all dirt collected therein without the necessity of the operator performing the squeezing or wringing action by hand. In the event that water would be squeezed from the mop into a bucket, a projecting hook 30 is provided on the under side of the head 2, whereby the mop may be suspended over the edge of a bucket and the squeezing or ringing action performed to direct the refuse water into

the bucket, whereby it may be suitably disposed of.

Having thus described this invention, what we claim and desire to secure by Letters Patent is:

1. A device such as described comprising a handle; a roller on an end of said handle; a pressure roller pivotally mounted on said handle relative to said first mentioned roller; tension means for maintaining said rollers in adjustable relationship; a manually operable means for separating said rollers; a flexible mop adapted to be retained between said rollers; and mechanical means on said handle for moving said mop between said rollers.

2. A device such as described comprising a handle; a roller on an end of said handle; a pressure roller pivotally mounted on said handle relative to said first mentioned roller; tension means for maintaining said rollers in adjustable relationship; a manually operable means for separating said rollers; a flexible mop adapted to be adjustably retained between said rollers an arm on said mop slidably retained on said handle and means on said handle engaging said arm for sliding said arm and mop relative to said handle.

3. A device such as described comprising a handle; a roller on an end of said handle; an auxiliary roller pivotally mounted on said handle relative to said first mentioned roller; a lever secured to said last mentioned roller for moving the same into open and closed positions relative to said handle roller; a mop adapted to be adjustably retained between said rollers; co-operating means on said mop and handle whereby said mop may be moved relative to said rollers; and spring means on said handle connected to said lever for maintaining the said roller in either the open or closed position.

4. A device such as described comprising a handle; a roller on an end of said handle; an auxiliary roller pivotally mounted on said handle relative to said first mentioned roller; a lever secured to said last mentioned roller for moving the same into open and closed positions relative to said handle roller; a mop adapted to be adjustably retained between said rollers and a spring tensioned arm pivoted to said handle and having said lever eccentrically pivoted thereto for maintaining said roller in either the open or closed position.

5. A device such as described comprising a handle; a roller on an end of said handle; an auxiliary roller pivotally mounted on said handle relative to said first mentioned roller; a lever secured to said last mentioned roller for moving the same into open and closed positions relative to said handle roller; a mop adapted to be adjustably retained between said rollers co-operating

means on said mop and handle whereby said mop may be moved relative to said rollers; and a spring tensioned arm pivoted to said handle and having said lever eccentrically pivoted thereto for maintaining said roller in either the open or closed position.

5 In testimony whereof, we have hereunto

set our hands at San Francisco, California,
this 10th day of April, 1922.

JULIUS DUSEVOIR.
ARCHIBALD W. SLOAN.

In the presence of—

LINCOLN V. JOHNSON.
